Attorney

UNITED STATES PATENT OFFICE.

WAYNE S. SEARLES, OF PROVIDENCE, RHODE ISLAND, ASSIGNOR TO UNIVERSAL OPTICAL CORPORATION, OF PROVIDENCE, RHODE ISLAND, A CORPORATION OF RHODE ISLAND.

OPHTHALMIC MOUNTING.

Application filed May 25, 1922. Serial No. 563,692.

To all whom it may concern:

Be it known that I, WAYNE S. SEARLES, a citizen of the United States, residing at Providence, in the county of Providence and

5 State of Rhode Island, have invented certain new and useful Improvements in Ophthalmic Mountings, of which the following is a specification.

This invention relates to improvements in 10 ophthalmic mountings, and has for its object to provide a non-metallic rim for embracing the eye-wire of the mounting, which rim is grooved internally to receive the eye-wire, the stock of the rim on one of the side 15 edges of the groove being less than that of the opposite side thereof to facilitate snapping the rim over the wire after the ends of the rim are secured to the wire.

With these and other objects in view, the 20 invention consists of certain novel features of construction, as will be more fully described, and particularly pointed out in the appended claims.

In the accompanying drawings:

25 Figure 1 is a front elevation illustrating an eyeglass mounting of my improved construction and showing the ends of the non-metallic rim as being secured to the eye-wire at points adjacent the end pieces of 30 the wire.

Figure 2 shows a portion of the non-metallic rim as broken away and illustrating the rivets for securing its ends to the eye-wire as set on an angle to the diametrical 35 axis of the lens through the eye-wire.

Figure 3 is an enlarged transverse section 40 through the eye-wire showing the non-metallic rim as being formed thinner on one edge than on the other to facilitate its being snapped over the metal eye-wire after its ends have been secured thereto.

Figure 4 is an edge view illustrating the non-metallic rim as having been secured at its ends to the eye-wire, the body portion 45 of the rim being in position to be snapped over the eye-wire.

With reference to the drawings, 10 designates the eye-wires of an ophthalmic or eyeglass mounting, which are connected together 50 by a bridge 11, and the ends of each of the eye-wires are provided with end pieces 12 through which the ends of the wire are connected in the usual way about the lens and which end pieces also serve as the connection for the temples 13.

The eye-wire 10 is designed to be covered or inclosed by a non-metallic rim 14 which may be made of any suitable material such as celluloid, zylonite or other material.

In order to connect this non-metallic rim 60 to the eye-wire and have the same tight and firm on the wire I first cut the rim to exactly the right length to fit tightly upon the wire and then attach the end portions 15 of the rim to the eye-wire at points adjacent 65 the end pieces by means of rivets or pins 16 while the rim is set at an angle to the wire in the position illustrated in Figure 4. I then force or crowd this rim inwardly and finally snap it over the eye-wire to fit closely 70 around the same.

In order to cause this rim to spring outwardly and yield sufficiently to be snapped over the eye-wire I preferably form the inner edge 17 of this rim considerably thinner 75 than the opposite or outer edge 18 thereof so that upon forcing the rim over the wire the thin edge will stretch and yield sufficiently to permit the rim to be snapped into 80 position.

In some instances it is found desirable instead of passing rivets or pins 16 radially through the ends of the rim, to set these rivets or pins on an angle as best illustrated in Figure 2, inclined towards the end pieces 85 whereby they are adapted to offer the maximum resistance to the strain incident to snapping the rim over the wire and so firmly retain the ends of the rim to abut closely 90 against the end pieces 12.

By my improved construction, these rims may be readily positioned on the eye-wire and when so positioned fully cover the eye-wire particularly when observed from the front of the mounting.

The foregoing description is directed solely towards the construction illustrated, but I desire it to be understood that I reserve the privilege of resorting to all the mechanical changes to which the device is 100 susceptible, the invention being defined and limited only by the terms of the appended claims.

I claim:

1. An eyeglass mounting comprising a 105 pair of metallic eye-wires connected by a bridge, the opposite ends of each eye-wire being connected by end pieces, an internally grooved non-metallic rim embracing the eye-wire, said groove being offset from a medial 110

line through the rim, and the ends of said rim being secured adjacent said end pieces.

2. An eyeglass mounting comprising a pair of metallic eye-wires connected by a bridge, end pieces at the opposite ends of each of said wires for connecting the ends of the wire, a non-metallic rim embracing the eye-wire grooved internally to receive

said wire, the stock of said rim on one side edge of the groove being of a thickness less than that on the opposite side of the groove to facilitate the snapping of the rim over the wire, and the ends of said rim being secured to the eye-wire adjacent its end pieces.

In testimony whereof I affix my signature.

WAYNE S. SEARLES.
